Nos. 1344

J. Steffe and J. H. Sailor, of Philadelphia, Pa, assors. to,
Cox, Whitman & Cox, of same place,
Letters Patent No. 1344, Dated Nov. 13th, 1860.

The schedule referred to in these Letters Patent and making part of the same.

To all whom it may concern:

Be it known that we J. Steffe and J. H. Sailor, have invented or produced a new and original design for the plates of a stove, termed the "Arctic"; and we do hereby declare the accompanying drawing and following explanation of the same to form a full, clear and exact description and illustration of the said design. The figures in the drawing representing the stove as viewed from different points.

A is the ornamental bottom plate of the stove. B, the circular base having ornaments in bas-relief and supporting the egg-shaped body C which is ornamented with projecting flutes and which has a perforated and ornamented annular guard D. Above the body C is ring E, edged with a wood moulding and above this ring is the cylindrical portion G, of the stove composed of four plates, each plate having the foliated ornaments represented in the drawing and the front plate of the four having a door H, with openings edged with foliated ornaments.

The whole is surmounted with an ornamental cap which
